UNITED STATES PATENT OFFICE.

EDWIN FABIAN AND FREDRIK WIDMARK, OF ST. PAUL, MINNESOTA.

CAR-COUPING.

SPECIFICATION forming part of Letters Patent No. 717,664, dated January 6, 1903.

Application filed April 4, 1902. Serial No. 101,351. (No model.)

To all whom it may concern:

Be it known that we, EDWIN FABIAN and FREDRIK WIDMARK, citizens of the United States, residing at St. Paul, in the county of Ramsey and State of Minnesota, have invented certain new and useful Improvements in Car-Couplings; and we do declare the following to be a full, clear, and exact description of the invention, such as will enable others skilled in the art to which it appertains to make and use the same, reference being had to the accompanying drawings, and to the figures of reference marked thereon, which form a part of this specification.

Our invention relates to improvements in car-couplings, and has for its object the providing of improved means for keeping the draw-head and draw-bar of a coupling normally in a central position. This object we attain by the novel construction and arrangement of parts illustrated in the accompanying drawings, in which—

Figure 1 is a sectional front view of a draw-bar at the point where it rests on the stirrup of the car, with stirrup and adjacent timbers shown. Fig. 2 is a top view of the stirrup or lowest piece in Fig. 1. Fig. 3 is a modification of Fig. 1. Figs. 4 and 5 are modifications of the antifriction-roller used in the stirrup.

Referring to the drawings by reference-numerals, 1 is the draw-bar of the coupling. It is provided in its under side with a longitudinal groove 39, resting upon an antifriction-roller 38, mounted in a cavity 36 of a stirrup 35, suitably secured to the timbers 70 71 of the car and provided with openings 37 in the bottom of its cavity for the escape of flying snow, rain, and sand. In heavy freight-car couplings we prefer to let the roller 38 rest upon a V-shaped or centrally downward-bulged bottom of the cavity 36; but we may also, especially for lighter cars, make the roller with trunnions, like 72 in Fig. 4, and place them in suitable bearings 73 in the stirrup; or, as a further modification, the trunnions may be flat, as at 72^x in Fig. 5, and formed of the ends of a shaft 74, on which the roller revolves. In using this shaft the flattened ends are dropped edgewise down into

the notches 73 in the stirrup and remain in that position until the shaft becomes considerably worn by the roller on the upper side. Then the shaft may be turned upside down and placed again in the notches until the other side is also worn out of shape, when a new shaft is substituted. If ever through any accident the shaft or roller, or both, should get lost, or it should become necessary to use a common draw-bar on said stirrup, it will be seen that the stirrup, being straight at its upper edges, will serve as well as any ordinary stirrup until roller and the proper draw-bar may be again provided, and when provided it will be understood that the arrangement set forth keeps the draw-bar in central position with perfect ease and certainty and with a minimum friction.

The practical application of this draw-bar support to couplings will be found more fully set forth and claimed in our application filed February 2, 1902, Serial No. 95,002.

We are aware that prior to our invention draw-bars have been made with a bottom guide, which, although of great crudeness and friction, prevent us from claiming a bottom guide broadly; but

What we claim, and desire to secure by Letters Patent, is—

1. In a car-coupling the combination with a draw-head or body of the coupling having a longitudinal inverted-V-shaped groove in its under side, of a stirrup adapted to support the coupling, said stirrup consisting of a horizontal bar straight at its top and provided in the middle with a pocket or cavity having a bottom inclining from both sides toward the middle of the bar, an antifriction-roller guided in said pocket, resting on its doubly-inclined bottom and supporting the coupling.

2. In a car-coupling the combination with a draw-head or body of the coupling having a longitudinal inverted-V-shaped groove in its under side, of a stirrup adapted to support the coupling, said stirrup consisting of a horizontal bar straight at its top and provided in the middle with a pocket or cavity having a bottom inclining from both sides toward the middle of the bar, an antifriction-

roller guided in said pocket, resting on its doubly-inclined bottom and supporting the coupling, and perforations in the bottom of said pocket, substantially as and for the purpose set forth.

3. A car-coupling having an antifriction-roller interposed between its under side and the stirrup supporting it, and a central longitudinal groove in the bottom side of the coupling, adapted to rest on the roller and

hold the coupling central against accidental side motion.

In testimony whereof we affix our signatures in presence of two witnesses.

EDWIN FABIAN.
FREDRIK WIDMARK.
